UNITED STATES PATENT OFFICE.

ROBERT W. SCOTT, OF PHILADELPHIA, PENNSYLVANIA.

SEWING-MACHINE.

SPECIFICATION forming part of Letters Patent No. 395,005, dated December 25, 1888.

Application filed August 24, 1888. Serial No. 283,628. (No model.)

To all whom it may concern:

Be it known that I, ROBERT W. SCOTT, a citizen of the United States, and a resident of Philadelphia, Pennsylvania, have invented 5 certain Improvements in Sewing-Machines, of which the following is a specification.

The object of my invention is to provide a double-stitch sewing-machine with an attachment whereby it is rendered available for the 10 production of an improved trimming for fabrics of the general character forming the subject of J. D. Morley's application for Patent bearing even date herewith, Serial No. 283,611, and of the special character set forth in my 15 application, likewise bearing even date herewith, Serial No. 283,627. This object I attain in the manner hereinafter set forth, reference being had to the accompanying drawings, in which—

20 Figure 1 is a side view of a sewing-machine with my improved attachment. Fig. 2 is an end view of the attachment. Fig. 3 is a plan view of the same; and Figs. 4, 5, and 6 are diagrams illustrating the operation of parts 25 of the machine.

My invention can be applied to any sewing-machine having stitch-forming mechanism adapted to form two parallel rows of stitches some distance apart. In the present instance 30 I have shown it as applied to a machine having a needle-bar with two needles, x x' , which operate in conjunction with two vibrating looper-hooks, y y' , the latter being carried by a rock-shaft, a , an arm, a' , on which is connected by a link, a'' , to an arm, b' , on a second rock-shaft, b , parallel with the first, this latter shaft having an arm, d , which is acted 35 upon by a cam, f , on the main or driving shaft g of the machine, so as to impart a rock-40 ing movement to said shaft b . This construction of machine, however, is in common use, and forms no part of my invention. On the bed-plate of the machine, however, is a frame, A , in which is a bearing for a shaft, B , having at the front end a worm-wheel, h , which 45 is operated by a worm, h' , on the main driving-shaft g of the machine, the rear end of the shaft B having a composite cam, D , comprising a peripheral cam, i , and a side face-cam, i' . The peripheral cam acts upon an arm, k , which is secured to a rock-shaft, k' ,

adapted to a suitable bearing on the bed of the machine and carrying an arm, n , which terminates close to the needle x' of the machine and has an opening serving as a guide 55 for a thread; or, it may have more than one opening, so as to guide more than one thread, if desired. The face-cam acts upon one arm of a bell-crank lever, F , the other arm of which is connected to a slide, G , guided in a 60 suitable bearing on the frame A , and forked at the outer end for connection to a pair of levers, I I' , which are located in advance of the needles and are hung to a suitable projection on the head of the machine, one fork 65 of the slide being connected to the lever I between the fulcrum of the same and the lower end, while the other fork of the slide is connected to the lever I' at a point beyond the fulcrum of the same, the consequence be-70 ing that as the slide G is reciprocated in either direction movement in opposite directions will be imparted to the two levers I I' , which are provided at their lower ends with openings serving as thread-guides. 75

The face-cam i' is so formed that the levers I I' will be moved from the position shown in Figs. 1 and 4, where the ends of the levers are outside the line of the needles x x' , to the position shown in Fig. 5, where the ends of the 80 levers are inside said line, and then to the position shown in Fig. 6, where the ends of the levers are outside the line of the needles, but are in a position the reverse of that shown in Figs. 1 and 4, the next movement of the 85 levers being back again to the position shown in Fig. 5, and then again to the position shown in Figs. 1 and 4.

In making the trimming shown in my application above referred to the levers occupy 90 the extreme positions shown in Figs. 4 and 6 for a very short time only, preferably during the formation of but two stitches, but occupy the intermediate position for a much longer time, so that after a cross-thread is bound 95 into each of the parallel rows of stitches a number of stitches will be formed by the sewing mechanism before the cross-threads are again bound in by the same, so that said threads are laid at an angle from one row of 100 stitches to the other and cross each other in their passage.

The peripheral cam *i* of the composite cam *D* is such as to impart to the arm *n* a movement whereby its guide is carried back and forth in front of the needle *x'*, and in 5 making the trimming shown in my said application the guide remains but a short time inside the line of the needle and a longer time on the outside of said line, so as to form the loops or scallops on the edge of the trimming. 10 It will be evident, however, that the movements of this lever, as well as those of the levers *I I'*, will be altogether dependent upon the character of the trimming to be produced.

Having thus described my invention, I 15 claim and desire to secure by Letters Patent—

1. The combination, in a sewing-machine, of stitch-forming mechanism having two needles for producing two parallel lines of 20 stitches, one or more thread-guides located in front of the needles and swinging from one to the other, a supplementary thread-guide swinging in front of one of the needles only, and mechanism for vibrating said thread-guides, substantially as specified. 25

2. The combination, in a thread-guiding attachment for sewing-machines, of a pair of levers forming thread-guides, with a slide hav-

ing a forked end, one arm connected to one lever on one side of the fulcrum and the 30 other arm connected to the other lever on the other side of the fulcrum, and with means for reciprocating said slide, substantially as specified.

3. The combination, in a sewing-machine, 35 of stitch-forming mechanism having two needles for producing two parallel lines of stitches, a pair of pivoted levers forming a duplex thread-guide in front of the needles, a forked slide for operating said levers, a 40 rock-shaft having a supplementary guide-arm acting in conjunction with one of the needles, an arm on said rock-shaft, a bell-crank lever connected to the forked slide, a combined peripheral and face cam for actuating 45 said arm and lever, and worm-gearing whereby the cam-shaft is driven from the main shaft of the machine, all substantially as specified.

In testimony whereof I have signed my name 50 to this specification in the presence of two subscribing witnesses.

ROBERT W. SCOTT.
